ATTORNEY

UNITED STATES PATENT OFFICE.

JOSEPH HARRIS, OF WEST TORONTO, ONTARIO, CANADA.

ADJUSTABLE TOOL.

1,264,922.

Specification of Letters Patent.

Patented May 7, 1918.

Application filed May 31, 1917. Serial No. 172,031.

To all whom it may concern:

Be it known that I, JOSEPH HARRIS, a subject of Great Britain, residing at West Toronto, in the Province of Ontario and 5 Dominion of Canada, have invented certain new and useful Improvements in Adjustable Tools, of which the following is a specification.

This invention relates to hand tools, and 10 particularly to that type of tool wherein rotary or reciprocatory movement is required for its operation, and aims primarily to provide improved means for angularly adjusting the operative end of the tool with 15 respect to the driving shaft, whereby the tool is rendered applicable to places or positions impossible of access without a tool of such construction.

A further object of the invention is to 20 provide a tool of the character briefly set forth, which is equipped with improved means for holding the tool in its various positions of adjustment.

A still further object of the invention is 25 to provide an angularly adjustable tool which has its drive and driven shaft positively held in operative engagement, which embodies but few simple, inexpensive and readily assembled parts, which has its various 30 movable parts so assembled and constructed as to minimize the opportunity for wear or breakage, which is capable of being readily applied to the ordinary carpenter's 35 brace, and which will prove thoroughly efficient in the attainment of the ends set forth.

With these objects in view together with others which will appear as the description 40 proceeds, the invention resides in the novel formation, combination, and arrangement of parts, all as will be described more fully hereinafter, illustrated in the drawings, and particularly pointed out in the claims.

In the drawings:

45 Figure 1 is a longitudinal sectional view taken through a tool constructed in accordance with the invention,

Fig. 2 is a bottom plan view of the device illustrated in Fig. 1, and

50 Fig. 3 is a detail fragmentary section taken through the angularly adjustable casing, and illustrating the means for holding the same in adjusted position.

55 Referring now particularly to the drawings, 5 and 6 represent respectively the casings which are used in carrying out the

invention, and which are adapted to house the drive and driven shafts of the tool, respectively. These casings are, in the present instance, rectangular in cross section, and 60 are open at their adjacent ends, the casing 5 fitting within the open end of the casing 6 as shown. The interfitting ends of these casings are pivoted together as indicated at 65 7, and a wing-nut 8 may be used in connection with one of the pivots to tightly bind the casings together so as to hold the same in adjusted position. It is obvious from this description, therefore, that these two casings may be adjusted in various angular 70 directions, and upon tightening of the wing-nut 8, the said casings will be firmly held in their various positions of adjustment.

The casing 6 carries the working tool, and for this purpose is provided with a central 75 and longitudinally disposed sleeve 9, which constitutes a bore for the tang or shank of the tool. This sleeve at its rear end is provided with inwardly projecting flange 11, which engages the shouldered rear end of 80 the tool shank, and a removable collar 12 may be secured to the reduced end of the tool shank upon the exterior of the flange 11, this construction permitting of the tool being rotated, but holding the same against 85 longitudinal movement in the casing. The tool in the present instance is illustrated as being a boring bit, but it will be understood that a screwdriver or any other type of tool which depends for its operation upon 90 rotary or oscillatory movement may equally as well be employed.

The casing 5 has disposed centrally and longitudinally thereof a drive-shaft 13, one 95 end of the said shaft projecting outwardly beyond the end of the said casing, and being squared or shouldered as at 14 to enable the same to be applied to a carpenter's brace or other driving apparatus. The outer end of the casing 5 is reduced as at 15, and forms 100 a bearing through which the drive shaft 13 projects. This bearing may be provided with packing as shown.

Fixedly secured to the drive shaft 13 within the casing 5 is a collar 16, against which 105 one end of an expansion spring 17 engages, the other end of the said spring seating against a collar 18 loosely inclosing the drive shaft and resting against the reduced end of the casing 5. This spring 17 thus normally 110 forces the inner end of the drive shaft toward the adjacent end of the tool shank. A

second collar 19 is adjustably secured upon the drive shaft 13 beyond the casing 5, and this collar limits the outward sliding movement of a disk or washer 20. A spring 21 5 bears at one end against the collar 20, and at its opposite end against a washer or disk 22, resting against the reduced end 15 of the casing 5. By adjustment of the collar 19, after engagement of the gears 23 and 24, the 10 tension of the spring 17 may be readily regulated to assure proper meshing of the gears 23 and 24, and the tension of the spring 17 may be varied in this manner, as desired when changing the angle of the driven shaft 15 with respect to the drive shaft 13. The collar 19 may be readily secured in adjusted position by the set screw 19' provided for the same. The springs 17 and 21 will co-operate to absorb any shocks upon the gears 20 23 and 24 during use of the tool and prevent stripping of the teeth of the gears.

The adjacent ends of the drive and driven shafts are provided with intermeshing gears 23 and 24, the said gears being so constructed 25 that a positive driving connection will be maintained between the same irrespective of the angular movement of the said shaft relative to each other. The springs 17 and 21 normally hold the drive shaft 13 with its 30 gear 23 in mesh with the gear 24 of the driven or tool shaft.

From this description it is apparent that I have provided an extremely simple and yet thoroughly efficient tool which is capable 35 of being adjusted so as to enable the same to be successfully used in places difficult of access. When the desired angularity of the tool is secured, the nut 8 may be rotated upon the pivot pin with which it is connected, whereupon the said casings are firmly held against accidental swinging movement. The shouldered end 14 of the 40 drive shaft 13 may then be secured in the clutch end of a carpenter's brace, or other

operating apparatus, and the tool is ready 45 for use.

While the present disclosure is that of what is believed to be the preferred embodiment of the invention, it is to be understood that the invention is not limited thereto, 50 but that various changes in the minor details of construction, proportion, and arrangement of parts may be resorted to if desired without departing from the spirit of the invention as defined by the appended 55 claims.

What I claim is:

1. In a tool of the class described, the combination with a pair of angularly adjustable rotatable shafts, intermeshing gears on 60 the adjacent ends of said shafts, a casing for each shaft, said casing being pivoted at their adjacent ends and being capable of being moved to angular positions, a collar on one of said shafts, an expansion spring engaging at one end with said collar and at its 65 opposite end with said casing, a second collar on said shaft, and an expansion spring engaging at one end with said casing and at its opposite end with said second collar. 70

2. In a tool of the class described, the combination with a pair of angularly adjustable rotatable shafts, intermediate gears on 75 the adjacent ends of said shafts, casing for said shafts, pins for pivotally connecting said casings at adjacent telescoping ends, said casings being capable of being moved to various angular positions, and oppositely acting resilient members for one of said shafts to retain said intermeshing gears in 80 engagement with one another.

In testimony whereof I affix my signature in presence of two witnesses.

JOSEPH HARRIS.
